UNITED STATES PATENT OFFICE

1,984,976

TELEPHONE PAY STATION

George A. Long and William W. Long, Hartford, Conn., assignors to The Gray Telephone Pay Station Company, Hartford, Conn., a corporation of Connecticut

Application June 17, 1932, Serial No. 617,764

20 Claims. (Cl. 179—6.3)

Our invention relates to the class of apparatus above named, and an object of our invention, among others, is the production of a structure of this type that shall be simple in construction and particularly efficient in operation.

One form of a telephone pay station embodying our invention, and in the construction and use of which the objects herein set out, as well as others, may be attained is illustrated in the accompanying drawings, in which—

Figure 1 is a front view of an automatic telephone embodying our invention.

Figure 2 is a side view of the same.

Figure 3 is a rear view in elevation of the upper part of the telephone with the back board removed.

Figure 4 is a top view of the coin operated switch mechanism.

Figure 5 is a view in elevation of the same with the coin receptacle removed.

Figure 6 is a view similar to Figure 5 but looking in the opposite direction.

Figure 7 is a view of the mechanism shown in Figure 6, looking from the right thereof.

Figure 8 is a view similar to Figure 7 but looking in the opposite direction.

Figure 9 is a detail view, scale enlarged, illustrating the switch mechanism in position with the switch open.

Figure 10 is a similar view showing the parts in another position with the switch closed.

Figure 11 is a view similar to Figure 10, the switch being closed but the parts being in another and advanced position.

Figure 12 is a diagrammatic view illustrating the wiring of our improved telephone.

This invention relates to an automatic telephone pay station such as is shown and described in United States Patent to George A. Long, No. 1,383,472, dated July 5, 1921 and which embodies a system of coin chutes in which coins are introduced into the upper or receiving ends thereof as shown in Letters Patent granted to the said Long June 27, 1916, No. 1,188,666 for delivering coins to a system of chutes and signals as set forth and described in the Long United States Letters Patent No. 912,389 granted February 16, 1909. These signals may be of any desired character but preferably they are audible and consist of sounds from a bell or gong which is in resonant connection with the transmitter 6, whereby such signals are transmitted for audible recognition by the operator at a central office, such apparatus being fully set forth and de-

scribed in my United States Letters Patent No. 917,742 issued to the said Long April 6, 1909.

The pay station involved in the present case is automatic as embodied in my said Patent No. 1,383,472 whereby on the deposit of a coin or other token the user bridges a gap or break in the electric circuit, and by some other operation, as the taking of the receiver from the hook, another break in said circuit is made and the circuit is completed thereby enabling the user to dial and call a party in a manner that will be readily understood. If the party called responds to such call the coin deposited for the use of the instrument will be retained in the coin box, this being effected by the party called taking his receiver from the hook and in a manner readily understood by those skilled in the art. If the called party does not respond, then the coin will be returned to the user when his receiver is placed upon the hook and in a manner common to telephone operations and as will be readily understood.

Thus far the deposit of the coin, so far as the signals are concerned, performs no operation. If a long distance call is wanted the coin is deposited as hereinbefore described and then the user may dial the central office in a way that will be readily understood and as provided in the dialing apparatus. The user may then direct the central operator as to the call desired and the central operator may return the coin already deposited to the user and such central operator will also instruct the user as to the amount of other coin or tokens to be deposited. If a connection is made with the party desired the central operator, by the operation of a key at her disposal, will deliver the coins into the coin box in the apparatus. If it be found that the party desired cannot be had then the central office, by the operation of another key, will return the coin into the return chute to be obtained by the user. This apparatus for delivering the coins to the coin box forms an important feature of the present invention and is clearly illustrated in the accompanying drawings in which the numeral 13 denotes the back plate of a telephone apparatus having a case secured to its front face, the upper part 14 of said case containing the telephone and the coin operated mechanism and the lower portion or base 15 containing the coin receiving apparatus, embodying a coin drawer 16 and a coin return pocket 17. The telephone apparatus embodies a receiver hook 18 from which a receiver 19 is suspended, a transmitter 20 projecting from the front of the case and a dial 21.

rotatably mounted above the transmitter 20 and which is operatively connected with dial mechanism within the case.

A coin chute plate 22 is located within the case 14 this plate containing chutes or runways for the delivery of coins, inserted in the top of the case, to signaling devices as bells 23, gongs or the like. The case also contains telephone mechanism 24 arranged in any usual and suitable manner.

All of the parts thus far described will be found specifically mentioned and set forth in the patents hereinbefore mentioned, the coin chute mechanism being shown in Patent No. 917,742 and the telephone mechanism embodying the dial structure in Patent No. 1,383,472.

The coins are inserted through holes 25 in a coin plate 26, shown in Figure 1 and travel along the chutes in different paths depending upon the hole in which they are inserted, in such travel striking the signal devices and finally issuing at the discharge end 27 of the plate 22 at which point they are delivered to a hopper 28 formed as a mouth of a coin receptacle 29 located in the bottom portion of the case 14.

A supporting plate 30 extends across the upper part of the base portion 15 of the case, being mounted thereon as by means of flanges and as shown in Figure 3 of the drawings. The coin operated switch mechanism is supported on said plate, said mechanism comprising an electromagnet 31 consisting of a pair of coils with an armature 32, said armature and coils being constructed to impart a tipping movement to the armature in opposite directions in a manner that will be readily understood, said armature being pivotally mounted in a frame 33 supported by the magnets. The magnets, armature and members directly supported and actuated thereby are of old and well known construction and further and detailed description, apart from specific mention, is therefore omitted herein, said parts except in connection with members now to be described forming no part of the present invention.

A trigger 34 is pivotally mounted upon the frame 33, as upon a pivot 35, and projects into a slot in the lower part of the hopper 28 to be engaged by a coin passing through said hopper 50 into the receptacle 29. The trigger has a U-shaped portion 36 to which is fastened a flexible member or spring 37 the free end of which rests against a side part of the frame 33, as shown in Figure 8 of the drawings, to hold the trigger in its raised position, said trigger being movable in said slot under the influence of the weight of a coin and by said spring.

A switch actuating frame 38 is pivotally mounted as upon an arbor 39 extending through posts 40 projecting from opposite side parts of the frame 33, and as shown in Figures 4 to 8 of the drawings. A switch actuating arm 41 projects from the frame 38 and rests upon the top of a lug 42 projecting from the upper edge of the trigger 34. A cam finger 43 projects from the frame 38 and has a cam 44 engaged with a frame actuating roller 45 mounted on a pivot 46 secured to and extending from an ear 47 projecting downwardly from a rock plate 48 rigidly secured to the armature 32 and as shown in Figure 7 of the drawings and in dotted lines in Figures 9 to 11.

A switch controlling frame 49 of the same general U-shape as the frame 38 is pivotally mounted on the arbor 39 and has an outwardly

projecting switch supporting arm 50 and a downwardly projecting cam finger 51 having a cam 52 for engagement by the actuating roller 45, the fingers 43 and 51 being located preferably side by side and as shown in Figure 7 of the drawings, and the cams 44 and 52 being a little differently shaped and operating in a manner to be presently described.

The arm 41 is slightly offset to bring it substantially in the plane of the arm 50 and the cross part 53 of a switch supporting lever 54 is pivotally attached at its opposite ends to the arms 41 and 50, and as shown in Figures 9 to 11 of the drawings, and a switch opening spring 55 is tensioned against the cross part 53 and the arm 50 to move said parts downwardly, the cross part 53 turning on its pivot 56 in this action, in a manner to be hereinafter described, said spring also maintaining contact between the cam 52 and the roller 45.

A switch 57 is supported in the lower end of the switch supporting lever 54, as shown in Figs. 9 to 11 of the drawings, said switch comprising a case with a fluid conductor therein adapted to make contact with terminals 58 and 59 connected with wires 60 and 61, one of said wires, as 61, extending to a ground and the other of said wires, as 60, extending to one of the terminals of the electromagnet 31.

The telephones herein shown, including the calling mechanism comprising the dials 21, are normally inactive and become active upon the performance of certain acts on the part of the user or users of the instruments. In the apparatus shown herein the closing of two switches 35 is necessary to enable a party calling to initiate a call. One of these acts is the deposit of a coin which results in the following operation:

A coin having been inserted in one of the holes 25 passes along one of the chutes in the plate 22, striking a signal or signals, which effect may be disregarded at the present time. The coin drops from the chute into the hopper 28, striking the trigger 34, tilting it on its pivot and thereby moving the lug 42 from underneath the actuating arm 41, permitting the latter to drop from the position shown in Figure 9. Thereupon the frame 38 swings upwardly, pivoting on the arbor 39, and the lever 54 also pivots on its pivot 62 thereby tipping the lever 54 from the position shown in Figure 9 to the position shown in Fig. 10 and causes the liquid conductor in the switch 57 to bridge the contacts 58—59, thereby closing the switch at this point. In this movement of the frame 38 the cam 44 which is normally out of contact with the roller 45 is carried against said roller from the position shown in Figure 9 to the position shown in Figure 10.

The receiver 19 having been removed from its hook and the latter swinging upward in a manner common to structures of this class a switch 63 (see Fig. 12) is closed thereby completing the circuit so that the dial 21 may be operated in the usual manner for calling purposes.

If the party called responds the removal of the receiver 64 (see Fig. 12) from its hook will close the switch 65 and this act not only completes the talking circuit but it also energizes the magnet 31, tipping its armature in one direction to deliver the coin into the coin box 16, in a manner that will be readily understood and as particularly set forth and described in the aforesaid Patent No. 1,383,472 hereinbefore mentioned.

In the present instance the energizing of the magnet 31 swings a leaf 66, shown in dotted out-

line in Figure 3, to the right and from underneath a trap 67 and the latter tipping on its pivot delivers the coin on to the leaf which directs it through the outlet 68 into said coin box, a counterpoise returning the leaf to its normal position.

The leaf 66 is provided with a roller 69 that rolls in contact with the underside of the trap 67.

Should the party called not respond the magnet 31 will be so energized that its armature will tip in the opposite direction to that above described and the leaf 66 will be swung in the opposite direction, thereby delivering the coin through an outlet 70 and into the return pocket 17, where it may be obtained by the user.

15 The leaf 66 is actuated by the armature, in the structure herein shown, by means of a pin 71 projecting through a slot in the case (see dotted lines in Fig. 3) into a notch in a trap actuating lever 72, said lever being rigidly secured at its upper end to the rocking plate 48 that has tipping movement imparted to it by the armature 32 as it is tipped, as hereinbefore described.

20 The mechanism for operating the switch 57 is so arranged that the switch will remain closed until the movement of the parts is practically completed, this being essential in order that the magnet will not be deenergized and thus prevent a completion of the operation. Whichever direction the armature is tipped, as hereinbefore described, the roller 45 will pass upwardly from the position shown in Figure 10 to the position shown in Figure 11, thereby so engaging the cams 44 and 52 as to simultaneously rock both of the frames 38 and 49. This effects a raising of the switch 57 without any substantial tipping movement thereof with a result that the contact between the terminals 58—59 is maintained during this operation, and as shown in Figs. 10 and 11.

25 This tipping movement of the armature also raises the arm 41 above the lug 42 allowing the latter to pass under the arm under the influence of the spring 37 to retain said arm in its raised position until the next operation. When the magnet becomes deenergized and the armature returns to its normal position the roller 45 releases the cam 44 and the frame 49 is returned by the action of the spring 55 to the position shown in Figure 9, whereby the operation may be repeated when desired.

30 This switch may well be termed a gravity switch, in that it is the force of gravity that controls movement of the fluid conductor, as mercury, or other conducting substance, which has been found by us to be particularly advantageous for use in connection with telephone apparatus, as it enables the operation of the magnets to be controlled to a degree not possible with apparatus heretofore used in the operation of telephones.

35 If the calling party wishes a long distance call a coin is deposited as hereinbefore described and the receiver 19 is removed from the hook 18 thereby closing the two circuits as hereinbefore described at the switches 57 and 63, the wire 61 of the latter being connected with the ground 73 as hereinbefore explained. This enables the operation of the dial 21 and consequent actuation of the dialing mechanism 74 (shown diagrammatically in Fig. 12) to call the central office in a manner that will be readily understood by those skilled in the art, and as, for instance, by insertion of the finger in the hole designated by "0" on the dial. The operation of a button by the central operator in a manner that will be readily understood causes the magnet to deliver the coin to the

party calling in the manner hereinbefore described. Said operator also directs the party to deposit the proper coins or tokens to pay for the call, and these pass along the chutes in the plate 22 as hereinbefore described and into the coin receptacle 29.

40 If the connection with the party called is completed the operator at the central exchange presses a certain button and the coin mechanism is operated as hereinbefore described to deliver 10 coins into the coin box 16. If the connection cannot be obtained then the said operator by pressing another button operates the magnet 31 to deliver the coins into the return pocket 17.

45 The signals are effective when the long distance calls are desired, as said signals being in resonant connection with the talking circuit the operator at the central exchange is enabled, by means of the sounds, to determine that the proper coins or tokens have been deposited to pay for the call. 15 The diagrammatic illustration in Fig. 12 will be readily understood by those skilled in the art of telephone construction and operation without further and detailed description, other than as contained herein, this wiring and other electrical 20 mechanism being of old and well known construction and the connections through the telephone exchange being well understood, the present invention residing in the combination of certain mechanisms hereinbefore explained, in combination 25 with the telephone apparatus, which enables the ordinary automatic telephone to be operated through the medium of coins or tokens deposited for use of the instruments for local calls, or for long distance calls which may be obtained by aid 30 of an operator at the central exchange. 35

50 In accordance with the provisions of the patent statutes we have described the principles of operation of our invention together with the device which we now consider to represent the best embodiment thereof; but we desire to have it understood that the device shown is only illustrative, and that the invention may be carried out by other means and applied to uses other than those above pointed out.

55 We claim:

1. A telephone pay station comprising circuit connections, a telephone receiver support mounted for shifting movement and coin operated means conjointly effective to control the circuit 50 of which said connections form a part, said coin operated means comprising a switch including a medium movable to opening and closing positions and inherently capable of remaining in either of said positions or to move to the other position, and means for moving said switch while delaying operation of said medium, said means being movable in opposite directions to effect the foregoing operations, all combined with means for effecting the action by coins of different denominations of 55 signals of different characters.

60 2. A telephone pay station comprising circuit connections, a telephone receiver support mounted for shifting movement and coin operated means, said support and coin operated means 60 having devices including a switch embodying a medium movable to opening and closing positions and inherently capable of remaining in either of said positions or to move to another position, and means for moving said switch while delaying 65 operation of said medium, said means being movable in opposite directions to effect the foregoing operations, said devices being operatively associated with said support, and coin operated means 70 75

for conjoint action to close said circuit of which said connections form a part.

3. A telephone pay station comprising circuit connections, a telephone receiver support mounted for shifting movement, means operative with said support for controlling the circuit of which said connections form a part, and coin operated means comprising a switch including a medium movable to opening and closing positions and inherently capable of remaining in either of said positions or to move to another position to control the same circuit at another point and means associated with the switch and movable in opposite directions to effect the foregoing operations, the two controlling means being operative before control of said circuit can be obtained.

4. A telephone pay station comprising circuit connections, a mechanical device set in action by a subscriber, means governed by said mechanical device for controlling the circuit, coin operable means for also controlling said circuit, said coin operable means comprising a switch including a medium movable to opening and closing positions and inherently capable of remaining in either of said positions or to move to the other position, and means for moving said switch while delaying operation of said medium, said means being movable in opposite directions to effect the foregoing operations, the two controlling means being jointly effective, and coin operable means for producing signals of different characters.

5. A telephone pay station comprising circuit connections having two breaks, a telephone receiver support shiftably mounted, means operative with said support for bridging one of said breaks, and coin operable means for bridging the other break, said coin operated means comprising a case containing a conducting medium movable to opening and closing positions and inherently capable of remaining in either of said positions or to move to the other position, and means associated with the case and movable in opposite directions to effect the foregoing operations.

45 6. A telephone pay station comprising circuit connections, means operative by a coin for controlling the circuit of which said connections form a part, said means comprising a case containing a conducting medium movable to opening and closing positions and inherently capable of remaining in either of said positions or to move to the other position, and means for moving said case while delaying operation of said medium, said means being movable in opposite directions to effect the foregoing operations, and coin controlled signal means operable independently of the coin operative circuit controlling means.

60 7. A telephone pay station having means operable by a coin for causing the action of a signal, said means comprising a case containing a conducting medium movable to opening and closing positions and inherently capable of remaining in either of said positions or to move to the other position, means associated with the case and movable in opposite directions to effect the foregoing operations, audible signal means operable independently of the other means, and a telephone transmitter in resonant connection with said audible signal means.

70 8. A telephone pay station having distinct means for operating a signal, audible means operating as a signal, coin operated means for causing the operation of said signal means to produce signals of different characters, said coin operated means comprising a case containing a

conducting medium movable to opening and closing positions and inherently capable of remaining in either of said positions or to move to the other position, and means for moving said case while delaying operation of said medium, said means being movable in opposite directions to effect the foregoing operations, and a telephone transmitter in resonant connection with said signal means.

5

9. A telephone pay station comprising circuit connections, a plurality of interdependent circuit controlling devices one of which is coin operable for controlling the circuit of which said connections form a part, said coin operable device comprising a case containing a conducting medium movable to opening and closing positions and inherently capable of remaining in either of said positions or to move to the other position, means associated with the case and movable in opposite directions to effect the foregoing operations, a telephone transmitter, means operable by coins for sounding signals of different characters and in resonant connection with said telephone transmitter, means for temporarily retaining the coins in a group after they have operated said signal means, and means for causing the coins to take different paths.

20

25

10. A telephone pay station comprising circuit connections, mutually dependent devices for controlling the circuit of which said connections form a part and one of which is coin operable, a device to temporarily retain the coin means for effecting the discharge of the coin from said device, means for maintaining the circuit during the discharge of the coin, said means comprising a switch including a medium movable to opening and closing positions and inherently capable of remaining in either of said positions or to move to another position and means for moving said switch while delaying operation of said medium, and said means being movable in opposite directions to effect the foregoing operations.

30

35

11. A telephone pay station comprising a telephone having a transmitter and a receiver, the station also involving a calling dial associated with the telephone, the telephone being normally inoperative by a subscriber for the transmission of intelligence to another subscriber, coin operated means at the station and including a switch comprising a medium movable to opening and closing positions and inherently capable of remaining in either of said positions or to move to the other position to render the telephone operative and to render the calling dial operative to make a local call to said other subscriber, means for moving said switch while delaying operation of said medium, said means being movable in opposite directions to effect the foregoing operations, and means for effecting the action by coins of different denominations of signals of different characters.

40

45

12. A telephone pay station comprising a telephone having a transmitter and a receiver, the station also involving a calling dial associated with the telephone, the telephone being normally inoperative by a subscriber for the transmission of intelligence to another subscriber, coin operated means at the station comprising a switch including a medium movable to opening and closing positions and inherently capable of remaining in either of said positions or to move to the other position to render the telephone operative and to render the calling dial operative to make a local call to said other subscriber, means associated with the switch and movable in opposite 70

60

65

70

75

75

directions to effect the foregoing operations, and means for effecting the action by coins of different denominations of audible signals of different characters.

- 5 13. A telephone pay station comprising a telephone having a transmitter and a receiver, the station also involving a calling dial associated with the telephone, the latter being normally inoperative by a subscriber for the transmission of intelligence to another local subscriber, coin operated means at the station comprising a switch including a member movable to opening and closing positions and inherently capable of remaining in either of said positions until moved to the other position to render the telephone operative and to render the calling dial operative to make a local call to said other subscriber, means for moving said switch while delaying operation of said medium, said means being movable in opposite directions to effect the foregoing operations, and means for effecting the action by coins of different denominations of audible signals of different characters, said audible signals being in resonant connection with said transmitter.

- 20 25 14. A telephone pay station comprising a telephone having a transmitter and a receiver, the station also involving a calling member associated with the telephone, the calling member being normally inoperative and the telephone being normally inoperative by a subscriber for the transmission of intelligence to another subscriber, coin operated means at the station comprising a switch including a member movable to opening and closing positions and inherently capable of remaining in either of said positions until moved to the other position to render the telephone operative and to render the calling member operative to make a local call to another subscriber, means associated with the switch and movable in opposite directions to effect the foregoing operations, and means for effecting the action by coins of different denominations of audible signals in resonant connection with the transmitter of said telephone.

- 30 35 40 45 15. The combination in a telephone instrument comprising a transmitter, receiver and calling dial, of a container having liquid (such as mercury) for closing a circuit, means affected through insertion of coins for causing said container to take a position to make the calling dial effective to establish talking conditions by closing said circuit, means for moving said container while delaying operation of the liquid therein, and distinct means at the central office to cause said container to return to its original position depending upon the disposition of the desired call.

- 50 55 60 16. The combination in a telephone instrument comprising a transmitter, receiver and calling dial normally inoperative for talking, of a container having liquid for closing a circuit, means operable through the insertion of a coin to cause said liquid to take a position to render the calling dial

effective for calling purposes, means for moving said container while delaying operation of the liquid therein, and separate and distinct means at the central office for returning the container and the liquid therein to its original and normal position.

17. A telephone pay station comprising circuit connections, a telephone receiver support mounted for shifting movement and coin operated means conjointly effective to control the circuit of which said connections form a part, said coin operated means comprising a switch, a switch actuating member for operating said switch, means for moving said member in one direction to actuate the switch, means for oppositely moving said member to effect delayed operation of the switch, and means for effecting the action by coins of different denominations of signals of different character.

18. A telephone pay station comprising circuit connections, a telephone receiver support mounted for shifting movement and coin operated means conjointly effective to control the circuit of which said connections form a part, said coin operated means comprising a switch, a switch actuating member for operating said switch, means for moving said member in one direction to actuate the switch, means for oppositely moving said member to delay operation of the switch and then for moving it differently to effect operation of the switch, and means for effecting the action by coins of different denominations of signals of different character.

19. A telephone pay station comprising circuit connections, a telephone receiver support mounted for shifting movement and coin operated means conjointly effective to control the circuit of which said connections form a part, a switch supporting member, a case supported by said member and having terminals projecting thereinto, a mobile electrical conductor contained within the case, means for moving said case while delaying shifting movement of said conductor, and means for effecting the action by coins of different denominations of signals of different character.

20. A telephone pay station comprising circuit connections, a telephone receiver support mounted for shifting movement and coin operated means conjointly effective to control the circuit of which said connections form a part, said coin operated means comprising a switch including a perpendicular lever with an element at one end thereof having a medium movable to opening and closing positions and inherently capable of remaining in either of said positions or to move to the other position, all combined with means for effecting the action by coins of different denominations of signals of different characters.

GEORGE A. LONG. 60
WILLIAM W. LONG.
